METHOD AND APPARATUS FOR MAINTAINING ADJACENT RAILWAY CARS ON A LEVEL PLANE

Theodore H. Schoepf and David M. Ritchie, Cincinnati, Ohio, assignors to The Cincinnati Traction Building Company, Cincinnati, Ohio, a corporation of Ohio

Application January 16, 1935, Serial No. 2,074

20 Claims. (Cl. 105—199)

This invention relates to a means and method of maintaining the equilibrium of railway cars. It is the object of this invention to provide a pendulum control for controlling the application of hydraulic pressure to the side bearings of railway cars in order to resist the rocking of the cars and to bring the cars back with their floors in a horizontal plane, in order to minimize rocking and swaying.

It is the object of this invention to provide especially for interconnecting the hydraulic system applied to the side bearings of the same car or adjacent cars to maintain the platform of the car or the platforms of adjacent cars in a horizontal plane, or to maintain the platforms of adjacent cars in the same plane. This latter feature is particularly advantageous in connection with cars that are articulated on a common truck and having a common passageway associated with a common truck and platforms of the adjacent cars.

It is the object to provide an interconnected hydraulic system associated with the respective side bearings so that hydraulic pressure can be applied to resist the downward movement of a car body on one side and simultaneously to apply hydraulic pressure to push the body down on the other side.

It is the object to provide means for quickly reversing this action, and means of determining the degree of pressure that will be applied in response to the degree of rolling and rocking that takes place in the car.

It is a further object to provide a means and method of returning the car quickly from a position of extreme rocking, as well as resist the movement of the car into such an extreme position. Thus this invention not only serves to prevent extreme rocking but is adapted to correct the rocking that takes place so quickly that it cannot be prevented.

It is a special object of this invention to provide a pendulum control of electric circuits which, in turn, control hydraulic valves and which also control the application of the hydraulic pressure through electrical means.

Referring to the drawings:

Figure 1 is a diagrammatic view of one end of one car showing the hydraulic and electrical control system.

Figure 2 is a modified form of electrical and hydraulic control shown diagrammatically.

Figure 3 is a detail view of a modified form of the pendulum control.

Figure 4 is a plan view of two adjacent cars

with cross-over hydraulic controls. This view is shown in connection with an articulated car, but the same principle is applicable to other types of adjacent cars.

Figure 5 is a modification of that portion of the circuit of Figure 2 including the field discharge resistance, showing the substitution of a capacitor.

Referring to the drawings in detail, and particularly to Figure 1, the numeral 1 is a car body 10 suitably supported upon a truck or trucks. This body is provided with side thrust bearings 2 provided with a connecting rod or piston rod 6 which extends into a cylinder 3 and is connected with a piston comprising a head 4 or a head 5. The side bearings 2 are mounted on the under side of the body remote from and at opposite sides of the center thereof, and the cylinders 3 are mounted upon the truck. This truck is generally designated 7. Any form of truck may be employed.

The body may be mounted upon the center bearing of the truck in the usual manner, or it may employ a trunnion in an articulated car, such as the trunnion designated 8. This trunnion is mounted in a trunnion socket or bearing plate 9, 25 suitably mounted upon the truck 7 in any desired manner. The details of this mounting are not important.

Returning to the side bearings and the hydraulic control therefor, when fluid pressure is applied through the pipe 10 to the cylinders 3, the piston head 4 and its connecting rod 6 ascend in the right hand cylinder (Fig. 1) while the piston head 5 and its connecting rod 6 descend in the left hand cylinder; when pressure is applied through pipe 11, the head 4 and its connecting rod 6 descend and the head 5 and its connecting rod 6 ascend in their respective cylinders 3. In other words, the application of pressure through the pipe 11 will either resist the downward movement of the side bearing member 2 or elevate it, while pressure through the pipe 10 will permit the side bearing member to descend by drawing the piston head 4 with the side bearing member 2 downwardly. The exact details of this construction are not important so long as the principle involved is employed of alternately applying pressure to resist the side bearing downward movement or to elevate the side bearing, and of applying pressure to remove that resistance or to cause the side bearing member to descend.

The pipe 10 on the right side is connected to the lower side of a cylinder 3 and on the left side to the upper side of a cylinder 3 while the pipe 11 is connected on the right side to the upper side

of a cylinder 3 and to the lower side of a cylinder 3 on the other side so that when the thrust on one side is upward, it is downward on the opposite side. These two groups of pipes are connected 5 to feed pipes respectively designated 12 and 13. The pipe 12 communicates with the chamber 14 in the hydraulic control valve 15. This chamber is formed by the walls of the valve 15, and by partitions 16 and 17. Partition 16 has the port 10 18 and partition 17 the port 19. The spring-pressed valve member 20 controls the port 19. The spring 21 cooperates to that end. A valve stem 22 connects the valve 20 to the valve member 23, which controls the port 18.

15 The pipe 13 communicates with the chamber 14 in the hydraulic control valve 15a which is similar to the hydraulic control valve 15, and which operates in the same manner. The chamber 14 of the valve 15a corresponds to the chamber 14 of the valve 15 and the other correspondingly numbered parts of the valve 15a likewise correspond to similarly numbered parts of the valve 15.

20 A controlling member, consisting of a stem 24 and solenoid core member 25, operates in the upper chamber 26 of the valve 15 and also in the valve 15a. The lower chamber 27 of each valve communicates with the pressure side of the pump through the common connection comprising pipe 28. The chamber 26 of each valve communicates 25 with the suction side of the pump through the common connection comprising pipe 29. The pump 30 supplies pressure to the pressure tank 31 and to the line 28. It is controlled, in its operation, through the hydraulic pressure switch 32, in order to maintain an even pressure. This switch is adapted, upon the production of predetermined pressure, to shut off the electrical motor which drives the pump, and upon decrease of the pressure to connect the pump motor to an electrical circuit so that the pump is driven. The pump 30 draws its supply from the discharge tank 33, which communicates with the pump 30 by means of the line 34. The discharge tank 33 is also connected to the suction line 29.

35 The valve system of Figure 1 operates as follows: Supported upon the center line of the car at a point adjacent the center of gravity, is a pivoted pendulum 35. The weight 36 is adapted to act as a contact member for engaging the right or left-hand contacts 37 and 38. The pendulum 30 is connected by the wire 39 to a source of current 40. This source of current 40, which may be an electric battery or some other similar agency, is connected on its other side through the wire 41, through the solenoid coil 43 and wire 42 to the contact 37. It is also connected through the wire 41, wire 44, solenoid coil 45 and line 46 to the contact 38. Thus, upon making the contact between 36 and 37 or 36 and 38 one of the valve stems 25 will be actuated to depress the valves 23 and 20 to permit the pressure from 28 to pass through the port 19, chamber 14 into the pipe 12 or 13, as the case may be. If the right-hand valve is actuated then the pressure is delivered through the pipe 12, and if the left-hand valve is actuated then the pressure is delivered through the pipe 13. When the pressure is so delivered it serves to check the tilting of the car in the direction of movement of the pendulum 35, and it 45 serves to restore that side of the car to its normal position. To cooperate in this there is a downward pressure applied on the other side of the car to restore the car floor to its normal horizontal position.

50 75 Referring to Figure 2, in the construction

shown in this figure it is possible to adjust the pressure applied hydraulically, according to the degree of swing or roll of the car. The pendulum 35 has the same contact weight 36. It is adapted to engage with the contacts 37 and 38, which control the opening of the hydraulic control valves 47 and 48. The contact 37 is connected by the wire 42 to the solenoid coil 43 surrounding the core 49, which constitutes the valve stem connected to the valve 50 in the valve casing 47. 10 This valve member 50 controls the port 51 in the partition 52 in 47. The opening of this port permits the flow of fluid through the valve 47. The coil 43 is connected at 53 to the line 54, which in turn, is connected to one side of the battery 40. 15 The other side of the battery is connected by the line 39 to the pendulum 35. The solenoid core 49 also carries the switch blades 55 and 56. The function of these switches 55 and 56 will be described later.

20 When the contact member 36 of the pendulum 35 engages the contact 38 it brings into operation the line 46, the solenoid coil 45 and the line 44, which is connected at 53 to the line 54 that is connected to one side of the battery 40. The other side of the battery is connected in circuit through the line 39 and contact weight 36. The solenoid core and valve stem 57 carries the valve member 58, which controls the port 59 in the partition 60 of the valve 48.

25 The valves 47 and 48 are thus able to control the application of hydraulic pressure from the hydraulic pressure source, designated 30. For instance, when the weight and contact member 36 moves to the right-hand, due to the tilting of the car to the right-hand, then the valve 50 is 35 opened and fluid passes from the right-hand side of the fluid source 30, through the pipe 61, through the port 51 into the pipe 62 to the pipe 63, which serves to force the side bearing at the 40 right-hand side upwardly or resist its downward movement. Simultaneously pressure is exerted through pipe 64 on the side bearing on the left-hand side to resist the rocking movement of the 45 car to the right and with a view to returning the car to its vertical position.

50 In the event the car rocks to the left-hand side then the valve 58 will be opened and the pressure will make its exit from the left-hand side of 30, through the port 59, having traveled through the pipe 65, and make its exit through the pipe 66 to the pipe 67, where it will serve to either resist or elevate the left-hand side of the car and simultaneously the pressure will pass into the pipe 68 on the right-hand side, with a 55 view to depressing that side of the car or resisting the elevation thereof.

55 The source of fluid pressure 30, shown in Figure 2, consists of a cylinder having springs 69 and 70 on opposite sides of the piston 71, which is actuated by the piston rod 72, which in turn, is actuated in either direction by the motor 73. This motor is provided with commutator brushes 74 and 75. Brush 74 is connected by the line 76 to the terminal 77. Brush 75 is connected by the line 78 to the terminal 79. The switch plate 80 connects the terminal 77 to the terminal 81 in the line 82. The terminal 83 in this line is connected by the switch blade 84, the terminal 85 connected into the line 86, which in turn, is connected to the battery 40.

60 65 70 Switch blade 87 connects terminal 79 to terminal 88, line 89, line 90 to solenoid coil 91 surrounding the core 92, which operates the switch 84. This coil is connected by line 93 to motor 75.

speed contact plate 94, and also by wire 95 to the left-hand motor speed contact plate 96. Wire 97 is also connected to line 89 and to the solenoid coil 98, which operates the core 99 that in turn operates the switches 80 and 81. The coil 98 is connected by wire 100 to the right-hand motor speed contact plate 101 and to the left-hand plate 102. Line 97 is connected to the wire 54, which in turn, is connected to the battery 40.

10 Returning to the lines 82 and 86, it will be noted that these two lines are connected together by the line 103 having a resistance 104. The purpose of the switch 84 is to cut out this resistance. The battery 40 is also connected to the line 105, which is connected to the line 106 having terminals 107 and 108.

15 The other side of the battery is connected by line 109 to the line 110 having terminals 111 and 112. Switch blade 56 is adapted to connect terminal 112 with terminal 113. Terminal 113 is connected by the line 114 to one side of the motor field 115, the other side of which is connected by the line 116 to the terminal 117, which is connected by switch blade 55 to the terminal 107. 20 Switch blade 56 also connects terminal 118, which is connected by line 114 to terminal 119, which is connected by line 120 to resistance 121 to the terminal 122.

25 The terminal 122 is connected by the switch plate to the terminal 124 and thence to line 125, back to line 116. When the switch blade 123 engages terminal 111 it connects it to terminal 126 and wire 125, thus cutting out resistance 121. When the switch blade 127 engages contact 108 it connects it to contact 128 and then by wire 129 to wire 114. 121 is a field discharge resistance to prevent a sudden and extreme rise of voltage when the field coil 115 is suddenly opened. Fig. 5 shows the substitution of a capacitor 121a for the field discharge resistance 12.

30 The operation of the apparatus shown in Figure 2 is as follows: When the car sways to bring the pendulum to one side of its vertical position, as in the case when the car tilts to the right-hand side, the weight contact member 36 engages the contact 37, which serves the purpose to open the valve 50, as heretofore described. The energization of the circuit, including the contact 37, results in bridging the contacts 112 and 113 by the switch 56. This brings the field 115 in circuit because the switch 55 also bridges the contacts 107 and 117. Therefore, field 115 is always in circuit, whether 36 is in engagement with contact 101 or 94.

35 When 36 engages 101 it energizes the armature circuit through the solenoid 98, causing switch plate 88 to bridge terminals 77 and 81, and switch plate 87 to bridge terminals 79 and 88. During this period the resistance 104 is in circuit. The motor operating the pump 30 begins to move to force the fluid through the piping system to correct the tilt of the body. If the tilt is very severe the contact pendulum 36 will move over the contact 94, energizing the solenoid 91 and closing switch 84, across the terminals 83 and 85, cutting the resistance 104 out of circuit and bringing about a higher speed of the motor armature 73, thereby delivering a higher hydraulic pressure to meet the greater roll.

40 If the pendulum swings to the left-hand it engages the contact 38, energizing solenoid 45, lifting valve 58 and closing the switch blade 123 across terminals 126 and 111, and also bring the switch blade 127 into engagement with terminals 108 and 128, thereby energizing the motor

45 field 115. It also results in energizing solenoid 98 with the same result as heretofore described. If the swing is more severe the contact pendulum weight 36 will engage with the contact 96 and energize the solenoid 91, with the result heretofore described.

50 When the solenoid 43 is energized, the motor 73 is polarized for operation in one direction while the polarity thereof is reversed for operation in the opposite direction when solenoid 45 is energized.

55 When the weight contact member 36 engages the contact 37, the bridging of the contacts 112 and 113 by switch plate 56 and the bridging of contacts 107 and 117 due to energization of solenoid 43 completes the following circuit: 40, 109, 110, 112, 56, 113, 114, 115, 116, 117, 55, 107, 105, and back to 40.

60 When, however, the weight contact member 36 engages the contact 38, the bridging of contacts 111 and 126 by switch plate 123 and the bridging of contacts 108 and 128 by switch plate 127 completes the following circuit: 40, 109, 110, 111, 123, 126, 125, 116, 115, 129, 128, 127, 108, 106, 105, and back to 40; in this case, the pole of the motor 73 which was positive during engagement of the member 36 with the contact 37 has become negative; the pole which was formerly negative has become positive.

65 Referring to Figure 3, there is provided a tilting pendulum arm pivoted at 130. The arm so pivoted is designated 131. On one end of the arm is carried a dash pot plunger 132, and on the other end a dash pot plunger 133. These plungers work in a U-shaped dash pot 134, containing the fluid 135. The movement of the fluid as the car tilts actuates the dash pot plungers 132 and 133, causes a movement of the arm 131 to bring into circuit the contacts 37 and 101, 94, 38, 102 and 96, as heretofore described.

70 It will be noted from Figure 4 of the drawings that the piping system can be connected either to thrust side bearings on opposite sides of the same car, or on bearings on different cars, as in the case when it is desired to preserve the floor alignment of the two cars that are adjacent one another, either for the purpose of maintaining the two cars against movement of their 45 floors out of a horizontal plane, or for the purpose of keeping the two cars so their platforms 50 will move together and be returned to the same horizontal plane with respect to one another, irrespective of the tilt of both bodies with respect to a horizontal position.

75 As shown in Figure 4, the adjacent cars No. 1 and No. 2 which are articulated upon and supported by a common truck (not shown) are each equipped with connections at each side, which connections comprise cylinders 3 mounted on the common truck with heads or pistons 4 and 60 5 provided with connecting rods or piston rods 6 which are connected to side bearings at opposite sides of the respective cars, as in Figures 1 and 2.

80 Each of the cars No. 1 and No. 2 is provided with a pump 30 connected by pipe 61 through valve 47 to pipe 62 and connected by pipe 65 through valve 48 to pipe 66. The pumps 30 and their controls and connections are identical with the pump 30 and its controls and connections described above and illustrated in Figure 2; the valves 47 and 48 and their controls and connections are likewise identical with the valves 47 and 48 and their controls and connections, as described above and illustrated in Figure 2.

The pipe 62 of car No. 1 is connected by pipe 64 to the upper end of the lefthand cylinder 3 of car No. 1 and by pipe 63 to the lower end of the righthand cylinder 3 of car No. 2; application of pressure through the pipe 62 of car No. 1, therefore, causes simultaneous exertion of force downwardly on the left side of car No. 1 and upwardly on the right side of car No. 2. The pipe 66 of car No. 1 is connected by pipe 67 to the lower side of the lefthand cylinder 3 of car No. 1 and by pipe 68 to the upper side of the righthand cylinder of car No. 2; application of pressure through pipe 66 of car No. 1 causes simultaneous exertion of upward force at the left side of car No. 1 and downward force at the right side of car No. 2.

The pipe 62 of car No. 2 is connected by the pipe 64 thereof to the upper side of the lefthand cylinder 3 of car No. 2 and by pipe 63 to the lower side of the righthand cylinder 3 of car No. 1; application of pressure through the pipe 62 of car No. 2 causes simultaneous exertion of downward force at the left side of car No. 2 and upward force at the right side of car No. 1. The pipe 66 of car No. 2 is connected by pipe 67 to the lower side of the lefthand cylinder 3 of car No. 2 and by pipe 68 to the upper side of the righthand cylinder 3 of car No. 1; application of pressure through pipe 66 of car No. 2 causes simultaneous exertion of pressure upwardly at the left side of car No. 2 and downwardly at the right side of car No. 1.

It will thus be seen that, through pump 30 of car No. 1, pressure is exerted simultaneously in opposite directions at the left side of car No. 1 and the right side of car No. 2. Likewise, force is exerted by the pump 30 of car No. 2 simultaneously at the left side of car No. 2 and the right side of car No. 1 and in opposite directions.

40 Due to the duplication of the pendulum control mechanism of Figure 2 for the pumps 30 and valves 47 and 48 for each of cars No. 1 and No. 2, tilting of one car in one direction will cause an opposing force to be applied to that car at one side and also to the adjacent car at the opposite side. If both cars are tilted, the opposing force is applied at opposite sides of each car, because both pumps 30 will be made operative to produce such force. When, upon tilting of both cars, pressure is applied through pipe 62 of car No. 1 to produce downward force at the left of car No. 1 and upward force at the right of car No. 2, pressure is also applied through pipe 62 to produce downward force at the left of car No. 2 and upward force at the right of car No. 1.

Likewise, upon tilting of both cars, when pressure is applied through pipe 66 of car 1, pressure is applied also through pipe 66 of car No. 2 and upward pressure is applied at the left side of both cars, and downward pressure is applied at the right side of both cars. When pressure is applied through a pipe 62, suction is applied through the corresponding pipe 66 and vice versa, as described above.

65 It will be understood that it is desired to comprehend within this invention such modifications as come within the scope of the claims and the invention.

Having thus fully described the invention, what is claimed as new and desired to be secured by Letters Patent, is:

1. In combination, a rail truck, a car body having laterally spaced side bearing means, and pivotally secured to said truck at a point therebetween for tilting movement about a fixed hori-

zontal axis, oppositely acting hydraulic means associated with the respective side bearing means for pressing the body downwardly or upwardly adjacent thereto, and means responsive to the tilt of said body for controlling said hydraulic means whereby hydraulic pressure can be applied simultaneously for resisting the downward movement of the body on one side and the upward movement of the body on the other side. 5

2. In combination, a rail truck, a car body having spaced side bearing means and pivotally secured to said truck at a point therebetween for tilting movement about a fixed horizontal axis, hydraulic means adjacent said side bearing means and associated therewith for pressing the body downwardly or upwardly, whereby hydraulic pressure can be applied simultaneously for resisting the downward movement of the body on one side and the upward movement of the body on the other side, and means controlled by the 15 tilting of the body for determining whether the hydraulic thrust on one side or the other will be up or down, whereby there is a coordinated thrust upwardly upon the low side of the body and downwardly on the high side of the body. 25

3. In combination, a rail truck, a car body having spaced side bearing means and pivotally secured to said truck at a point therebetween for tilting movement about a fixed horizontal axis, hydraulic means adjacent said side bearing means 30 and associated therewith for pressing the body downwardly or upwardly, whereby hydraulic pressure can be applied simultaneously for resisting the downward movement of the body on one side and the upward movement of the body on the other side, means controlled by the tilting of the body for determining whether the hydraulic thrust on one side or the other will be up or down, whereby there is a coordinated thrust upwardly upon the low side of the body and downwardly on the high side of the body, and means 35 for supplying pressure to said hydraulic means.

4. In combination, a rail truck, a car body having spaced side bearing means and pivotally secured at a point therebetween to said truck for tilting movement about a fixed horizontal axis, hydraulic means adjacent said side bearing means and associated therewith for pressing the body downwardly or upwardly, whereby hydraulic pressure can be applied simultaneously for resisting the downward movement of the body on one side and upward movement of the body on the other side, tilt responsive means controlled by the tilting of the body for determining whether the hydraulic thrust on one side or the other will be up or down, whereby there is a coordinated thrust upwardly upon the low side of the body and downwardly on the high side of the body, and means for supplying pressure to said hydraulic means, said tilt responsive means comprising a pendulum pivoted on said body and valve means controlled thereby for directing the hydraulic pressure in order to correct the tilt of the body. 55

5. In combination, a rail truck, a car body having spaced side bearing means and pivotally secured to said truck at a point therebetween for tilting movement about a fixed axis, hydraulic means supported on said truck adjacent said side bearing means associated with said side bearing means for pressing the body downwardly or upwardly, whereby hydraulic pressure can be applied simultaneously for resisting the downward movement of the body on one side and the upward movement of the body on the other side, 70 75

- tilt responsive means controlled by the tilting of the body for determining whether the hydraulic thrust on one side or the other will be up or down, whereby there is a coordinated thrust upwardly upon the low side of the body and downwardly on the high side of the body, means for supplying pressure to said hydraulic means, said tilt responsive means comprising a contact pendulum pivoted on said body and valve means controlled thereby for directing the hydraulic pressure in order to correct the tilt of the body, and electrically actuated means for actuating said valve means adapted to be brought in circuit by the movement of the pendulum.
15. 6. In combination, a rail truck, a car body having spaced side bearing means and pivotally secured to said truck at a point therebetween for movement about a fixed axis, hydraulic means supported by said truck and associated with said side bearing means for pressing the body downwardly or upwardly adjacent thereto, whereby hydraulic pressure can be applied simultaneously for resisting the downward movement of the body on one side and upward movement of the body on the other side, tilt responsive means controlled by the tilting of the body for determining whether the hydraulic thrust on one side or the other will be up or down, whereby there is a coordinated thrust upwardly upon the low side of the body and downwardly on the high side of the body, means for supplying pressure to said hydraulic means, said tilt responsive means comprising a contact pendulum pivoted on said body and valve means controlled thereby for directing the hydraulic pressure in order to correct the tilt of the body, electrically actuated means for actuating said valve means adapted to be brought in circuit by the movement of the pendulum, and a supplementary power source for energizing the electrical means so brought into circuit.
7. In combination, a rail truck, a tilting car body pivotally connected to said truck, hydraulically operated thrust means for thrusting upwardly and downwardly on said body on opposite sides of said pivotal connection, means to supply fluid pressure to said hydraulic means, hydraulic valve means for determining the direction of application of the pressure, a pendulum pivoted on the body, an electrical means controlled by and adapted to be brought into circuit with said pendulum for operating the electrical means to operate the valve means determining the course of the hydraulic pressure.
8. In combination, a tilting car body, hydraulically operated thrust means for thrusting upwardly and downwardly on said body on opposite sides thereof, means to supply fluid pressure to said hydraulic means to cause simultaneous operation of the hydraulic means in opposite directions, hydraulic valve means for determining the direction of application of the pressure, a pendulum pivoted on the body, an electrical means controlled by and adapted to be brought into circuit with said pendulum for operating the electrical means to operate the valve means determining the course of the hydraulic pressure, and supplementary electrical means controlled by said pendulum for controlling the total pressure of the hydraulic circuit according to the degree of tilt of the body.
9. In combination, a truck, a body mounted on said truck for tiltable movement about a horizontal axis, and extensible hydraulic connections between said body and said truck at opposite sides of said axis, each of said connections comprising a cylinder having therein a piston rigidly connected to a piston rod, each of said cylinders having hydraulic cross connection from the top thereof to the bottom of the other cylinder, and means to simultaneously apply pressure to one of said cross connections and suction to the other of said cross connections to simultaneously extend one hydraulic connection while contracting the other hydraulic connection.
10. In a control means for correcting the tilt of a car, a fluid tube, float members floating in the arms of said tube, a pivotal contact shaft connected to said float members and pivoted therebetween, and electrical contacts selectively engaged by said contact shaft according to the degree of tilt reflected in said fluid tube.
11. In combination, a rail truck, a car body, means on said truck to pivotally support said car body to permit it to rock, side thrust means, hydraulic means on said truck operating downwardly and upwardly upon said side thrust means to resist and correct the tilt of the body, a hydraulic pump connected thereto, hydraulic valves for selecting the direction of the fluid so pumped, and electrical means for controlling said pump and selecting the direction of movement of the hydraulic pressure.
12. In combination, a car body, means to pivotally support said car body to permit it to rock, side thrust means, hydraulic means operating downwardly and upwardly upon said side thrust means to resist and correct the tilt of the body, a hydraulic pump connected thereto, hydraulic valves for selecting the direction of the fluid so pumped, electrical means for controlling said pump and selecting the direction of movement of the hydraulic pressure, and electrical means for controlling the rate of said pump.
13. In an articulated car construction, a truck, adjacent car bodies having common articulation with said truck, side thrust bearings for said respective cars associated with said truck, hydraulic means for operating on said car bodies in association with the side bearings for simultaneously moving one portion of one body downwardly and another portion of another body upwardly with respect to said truck.
14. In an articulated car construction, a common truck, a pair of car bodies having their adjacent ends articulated for free lateral movement on said truck, hydraulic thrust means disposed on said truck and connected to each side of each of said bodies and adapted to thrust upwardly on one side and downwardly on the other side of each of said bodies, means to supply fluid to said hydraulic thrust means, and means to synchronize said thrust means connected to the respective car bodies so as to maintain the car bodies in substantially the same plane.
15. In an articulated car construction, a truck, a pair of car bodies articulated for free movement on said truck, hydraulic means connected to said truck and to each side of each of said bodies and adapted to thrust upwardly on one side and downwardly on the other side of each of said bodies, means to supply fluid to said hydraulic thrust means, and means to synchronize said thrust means connected to the respective car bodies so as to maintain the car bodies in substantially the same plane, said means being so arranged that the hydraulic thrust means will thrust downwardly on an upwardly moving side of one body and upwardly on the opposite side of the other body.
16. In a system of maintaining the bodies of a

plurality of connected cars having trucks in a predetermined relationship, hydraulic thrust means oppositely disposed with respect to the center line of each of said cars near the adjacent 5 ends thereof, said hydraulic means being interposed between the trucks and the car bodies, means to pivotally support the car bodies on their trucks, and means interconnecting the hydraulic thrust means of adjacent cars whereby they operate 10 in synchronism to maintain their car bodies in a predetermined relationship.

17. In a system of maintaining the bodies of a plurality of connected cars having common trucks in a predetermined relationship, hydraulic 15 thrust means oppositely disposed on either side of the center line of each of said cars near the adjacent ends thereof, said hydraulic thrust means being interposed between the common truck and the bodies of adjacent cars, means to 20 pivotally support the adjacent ends of the car bodies on the common truck, and means interconnecting said hydraulic thrust means of adjacent car bodies whereby they operate in synchronism to maintain said car bodies in a predetermined 25 relationship, said means being so arranged that the pipe conveying hydraulic pressure to the top of the hydraulic thrust means on one side of one body is connected to the bottom of the hydraulic thrust means on the opposite 30 side of the other body.

18. In a system of maintaining the bodies of adjacent cars having a common truck in a predetermined relationship, hydraulic thrust means disposed at opposite sides of the center line of 35 each of said cars near the adjacent ends thereof, said hydraulic thrust means comprising cylinders each having therein an oppositely acting piston with a rigid connecting rod and being interposed between the common truck and the car bodies, 40 means to pivotally support the car bodies on the truck, means interconnecting said hydraulic thrust means whereby they operate in synchronism to maintain said adjacent car bodies in a predetermined relationship, said means being so 45 arranged that a pipe conveying hydraulic pres-

sure to the top of the cylinder of the hydraulic thrust means on one side of one body is connected to the bottom of the cylinder of the hydraulic thrust means on the opposite side of the other body, and a common means responsive to the tilt of at least one of said bodies for applying hydraulic pressure to correct said tilt. 5

19. In a system of maintaining the bodies of adjacent cars having a common truck in a predetermined relationship, hydraulic thrust means 10 disposed on opposite sides of the center line of each of said cars near the adjacent ends thereof, said hydraulic thrust means comprising cylinders each having therein an oppositely acting piston with a rigid connecting rod and being interposed 15 between the common truck and the car bodies, means to pivotally support the car bodies on the truck, means interconnecting the cylinders of said hydraulic thrust means whereby they operate in synchronism to maintain said car bodies 20 in a predetermined relationship, said means being so arranged that a pipe conveying hydraulic pressure to the top of the cylinder of the hydraulic thrust means on one side of one body is connected to the bottom of the cylinder of the 25 hydraulic thrust means on the opposite side of the other body to cause simultaneous application of force in opposite directions by said last-named hydraulic thrust means, a common means responsive to the tilt of at least one of said bodies 30 for applying hydraulic pressure to correct said tilt, and means also responsive to the tilt of at least one of said bodies for controlling the degree of pressure of said hydraulic means in order to adjust it to the extent of the tilt. 35

20. In a method of maintaining two railway car bodies articulated on a common truck in substantial alignment against tilting, applying hydraulic pressure on one body downwardly from said truck as the body moves upwardly and upwardly from said truck on the opposite side of the other body as it moves downwardly. 40
